ATTORNEY

UNITED STATES PATENT OFFICE.

JAMES H. WHITNEY, OF BROOKLYN, NEW YORK.

DESIGN FOR A FLY-WHEEL FOR SEWING-MACHINES.

SPECIFICATION forming part of Design No. 14,436, dated November 20, 1883.

Application filed July 6, 1883. Term of patent 14 years.

To all whom it may concern:

Be it known that I, JAMES H. WHITNEY, a citizen of the United States, and a resident of Brooklyn, in the county of Kings and State of New York, have invented a new and original Design for Fly-Wheels for Sewing-Machines, of which the following is a specification.

My design is fully illustrated in the accompanying drawings, to which reference is made, and in which—

Figure 1 represents a side view of a fly-wheel for sewing-machines constructed according to my present design. Fig. 2 is a face or edge view of the same.

5 B is the rim of the wheel, and a is the hub. The rim is flat on one side, as shown in Fig. 1 and at B' in Fig. 2, and on its outer and inner circumferences are raised beads b, leaving a sunk surface between the said beads. The o arms are also formed with beads upon their edges, as shown in Fig. 1. These arms are formed of the letter A. The legs of the letter radiate from the hub A to the rim B, and are connected crosswise by the ordinary horizontal or crossstroke E of the letter A, said cross-stroke projecting with its ends beyond the legs of the letter A, and the ends of the said cross-stroke being beveled off, and their end surfaces, e, parallel with each other. Each of the said

letters A is intended to replace one of the arms 30 of the fly-wheel, and they are arranged, as in Fig. 1, three in number, in such a manner that the center line of each letter forms an angle of one hundred and twenty degrees with the center line of the next—that is to say, so that the 35 angle x x y is equal to the angle y x z and equal to the angle z x r. The hub C of the crank-pin is formed in the angle of one of the letters, as shown in Fig. 1.

What I claim as new, and desire to secure 40 by Letters Patent of the United States, is—

1. The design for fly-wheels, as shown, consisting of the rim B, hub a, and the capital letters A A A, forming the arms or connection between the said hub and rim. 45

2. The design for fly-wheels, as shown, consisting of the flat and beaded rim, the hub a, and the flat and beaded capital letters A A A, forming arms or connections between the said hub and rim. 50

In testimony that I claim the foregoing as my invention I have signed my name, in presence of two witnesses, this 30th day of April, 1883.

JAMES H. WHITNEY.
